SHARPENER

Israel Bien, San Francisco, Calif.

Application August 17, 1937, Serial No. 159,581

1 Claim. (Cl. 120—90)

This invention relates to improvements in sharpeners and has particular reference to a sharpener for chalk, such as, tailor's chalk.

The principal object of this invention is to produce a simple, inexpensive device which may be carried in the pocket and used when desired.

A further object is to produce a device of this character which will sharpen the chalk but which will not wear out the pocket of the user, or will 10 it injure the fingers thereof.

Other objects and advantages will be apparent during the course of the following description.

In the accompanying drawing forming a part of this specification and in which like numerals are employed to designate like parts throughout the same,

Fig. 1 is a side elevation of my device, showing the same in use;

Fig. 2 is a top plan view of Fig. 1 on an enlarged scale;

Fig. 3 is an end elevation of Fig. 2;

Fig. 4 is an end elevation of a piece of sharpened chalk; and

Fig. 5 is a cross sectional view taken on the line 5—5 of Fig. 2.

Tailor's chalk is cast in blocks and is relatively hard in comparison to the ordinary chalk used with black boards. Tailor's chalk is used for the purpose of marking upon cloth lines to be followed in stitching, positioning of buttons, etc. In order that the line may be accurate, it is necessary to sharpen this chalk along one side thereof so that the line made on the cloth will be clear and of fine proportions in counter-distinction to a heavy or wide line.

In the accompanying drawing wherein for the purpose of illustration is shown a preferred embodiment of my invention, the numerals 5 and 6 designate a pair of blocks, held together by

screws 7. Secured between the blocks 5 and 6 are plates 8 and 9, which plates have their upper margins extending beyond the margin of the blocks and spread, as best shown in Figs. 2, 3, and 5. These plates are each provided with an aperture 11 therethrough and have their ends turned in, as shown at 12 and 13. The said apertures permit the escape of shavings or chalk dust which accumulates behind the edges 12 and 13 during the sharpening operation. These in-turned ends 12 and 13 form scraping elements so that when the chalk is pressed between the diverging plates and moved longitudinally, as indicated in the arrow in Fig. 1, these edges 12 and 13 will contact the outer sides of the chalk A 15 and will scrape therefrom excess material until the chalk has been properly sharpened.

It will thus be seen that I have produced a device which will perform all the objects above set forth.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:

In a device of the character described, a pair of blocks, a pair of plates secured between said blocks, said plates each having a portion thereof diverging beyond the margin of said blocks, each of said plates having an aperture formed in its diverging portion, each of said plates having the ends of its diverging portion bent so as to form scraping elements angularly disposed with relation to each other.

ISRAEL BIEN.
